UNITED STATES PATENT OFFICE.

CHARLES C. BLAKE, OF BROOKLINE, MASSACHUSETTS, ASSIGNOR TO C. C. BLAKE,
INCORPORATED, OF BOSTON, MASSACHUSETTS, A CORPORATION OF NEW YORK.

MECHANICAL MOVEMENT.

1,284,865.

Specification of Letters Patent. Patented Nov. 12, 1918.

Original application filed March 27, 1916, Serial No. 86,958. Divided and this application filed February 18, 1918. Serial No. 217,771.

To all whom it may concern:

Be it known that I, CHARLES C. BLAKE, a citizen of the United States, residing at Brookline, in the county of Norfolk and 5 State of Massachusetts, have invented certain Improvements in Mechanical Movements, of which the following description in connection with the accompanying drawings, is a specification, like reference characters 10 act on the drawings indicating like parts in the several figures.

This invention relates to mechanical movements and has for its general object to devise a mechanism that will impart to a driven 15 member a bodily transferring movement in a curved path. The invention will be herein disclosed as embodied in a mechanism designed to oscillate a member bodily in a substantially U-shaped path, but it will be obvious from an understanding of the invention 20 that it is also applicable to mechanisms designed to move a member in paths other than that specifically described but which involve similar problems of motion.

25 The invention will be readily understood from the following description reference being made to the accompanying drawings in which,

Figure 1 is a plan view of the more important parts of a mechanism embodying 30 this invention;

Fig. 2 is a vertical, longitudinal, cross sectional view of the mechanism shown in Fig. 1, but showing the driven member in a 35 different position;

Fig. 3 is a vertical, transverse, cross sectional view of the mechanism shown in Figs. 1 and 2; and

Fig. 4 is a diagrammatic view showing the 40 manner in which the parts effect the desired movement of the driven member.

This application is a division of my pending application Serial No. 86,958 filed March 27, 1916 for improvements in heel lasting 45 machines. The machine shown in said application comprises mechanism for wiping the margin of the upper at the heel part of the shoe into lasted position on the sole receiving face of the insole and a tacking 50 mechanism that is moved automatically around the marginal portion of the heel end of the insole and operates during said movement to drive tacks through the lasted upper

to secure it in its lasted position. The mechanism shown in the present application 55 forms a part of the mechanism that guides the tacker around the heel end of the shoe.

It is obvious that in the machine shown in my parent application the tacker must be moved in a substantially U-shaped or 60 horse-shoe shaped path. This movement is imparted to the tacker by the driven member 2 which consists of a post on which two plates 3 and 4, respectively, are loosely 65 mounted so that they are compelled to partake of the bodily movement of the post 2 but can swing or pivot on this post. In other words, the member 2 forms a pivot pin for the plates 3 and 4. This post passes through a U-shaped slot 5 formed in a plate 70 6 that is rigidly secured to the frame 7 of the machine. It is held against vertical movement relatively to the plates 3, 4 and 6 by means of a head 8 that engages the lower 75 face of the plate 6, and a nut 9 that is threaded on to the upper end of the post 2 and brings up against a shoulder which prevents it from binding the plates 3, 4 and 6 together.

A slide 10 is mounted to reciprocate in a 80 horizontal way formed between the plate 6 and the frame 7 and has fixed to it a rack 11, as clearly shown in Figs. 1, 2 and 3. Another slide 12 is similarly mounted in the opposite side of the frame and has a rack 85 13 fixed thereto. Both racks are reciprocated by a pinion 14 mounted fast on the upper end of a rotatable shaft 15 which is oscillated through considerably more than half a revolution by mechanism that comprises 90 a worm wheel 16, fast on the lower end of the shaft 15, and a worm 17 that drives the worm wheel 16. This mechanism reciprocates the racks and consequently the slides 10 and 12 back and forth in their ways in 95 opposite directions. The two slides 10 and 12 run tangent to a disk 18 fast on the upper end of the shaft 15, and this disk is provided with a semi-cylindrical notch or recess 19 (see Fig. 4) which receives the 100 post 2 when this member is in the curved part of the slot 5 and which is designed to register with similar notches 20 and 21, respectively, formed in the slides 10 and 12, respectively. As clearly shown in Fig. 2, the 105 disk 18 is positioned in a recess formed for

it in the lower face of the plate 6, so that when the post 2 is positioned in the notch 19 of the disk 18 the face of the post opposite the notch is engaged by the wall of the slot 5. The post thus is compelled to move with the notch.

Referring now to Fig. 4, and assuming that the slides 10 and 12 are moving in the directions indicated by the arrows and also 10 that the post is positioned in the notches 19 and 21, which at this time are in register, the continued movement of the parts in the directions indicated enables the slide 12 to carry the post toward the left along the leg *a* 15 of the U-shaped slot 5. The direction of rotation of the worm 17, and consequently of the pinion 14 and disk 18, is reversed at or about the time that the post 2 reaches the end of this leg of the slot, whereupon the slide 12 20 moves the post back toward the right (Fig. 1) along the straight part *a* of the slot 5 and toward the curved portion. When the post arrives at the position in which it is shown in Fig. 1 the notch 19 in the disk 25 18 engages it and carries it around the curved part of the slot 5 and delivers it to the notch 20 of the slide 10, which then carries it along the straight part *b* (Fig. 1) of the U-shaped slot 5. When the motion 30 of the disk 18 and slides 10 and 12 is again reversed the motion of the post is reversed and this action is continued so long as this mechanism is allowed to run. The post 2, being free to rotate in the parts 3, 4 and 6, 35 rolls along the walls of the slot 5 with comparatively little friction. It will be noted that the edges of the slides 10 and 12 which are tangent to the periphery of the disk 18 lie on the pitch line of the racks 11 and 13.

From the foregoing description it will be understood that the slides carry the driven member 2 along the straight portions of its path of travel while the disk 18 carries 45 this member around the curved portion of its path of movement and transfers it from one of the reciprocating devices to the other at the proper times in its movement. This movement of the member 2 moves the plates 50 3 and 4 in a U-shaped path, but since these plates can have a pivotal movement relatively to each other about the axis of the post 2 certain variations in this path can be produced by suitable mechanism as clearly 55 explained in my parent application above designated.

The mechanism for driving the worm 17 is not shown herein since any suitable form of automatic reversing mechanism may be 60 used. If the mechanism driving the worm 17 operates at a uniform speed between its points of reversal, the post 2 will be moved along the slot 5 at a uniform rate of travel. If it is desired to give the post 2 a step by 65 step movement along its path, it is merely

necessary to drive the worm 17 intermittently by any one of several well known mechanisms.

While I have herein shown and described the best embodiment of the invention 70 of which I am at present aware, it is obvious that this embodiment may be modified in many ways without departing from the spirit or scope of the invention. It is obvious also that the underlying principles of 75 the invention are applicable to mechanisms designed to move a member in a different path from that in which the mechanism described moves the post 2 but which involve similar problems of motion. 80

What is claimed as new, is:

1. A mechanical movement having, in combination, a movable member and reciprocating and rotatable devices operative through direct engagement with said member to move it in a curved path. 85

2. A mechanical movement, having, in combination, a movable member, and reciprocating and rotatable devices operative through direct engagement with said member to oscillate it in a curved path. 90

3. A mechanical movement, having, in combination, a member mounted for movement in a path having straight and curved portions, and a plurality of devices, each mounted for movement in a fixed path but constructed and arranged to engage said member and move it along successive parts of its path. 95

4. A mechanical movement, having, in combination, a member mounted for movement in a path having straight and curved portions, and mechanism for oscillating said member in said path comprising a plurality of devices, each movable in a fixed path and constructed and arranged to engage said member and move it along its path into engagement with another of said devices. 100

5. A mechanical movement, having, in combination, a member mounted for movement in a curved path, and mechanism for moving said member back and forth in said path comprising a plurality of devices each movable in a fixed path and constructed and 115 arranged to act at different times on said member to move it along successive portions of its path. 110

6. A mechanical movement, having, in combination, a member mounted for movement in a path having straight and curved portions, and mechanism for moving said member along said path comprising a reciprocating device arranged to engage said member and move it along a straight portion of said path and another member movable about an axis and arranged to engage 125 said member and move it about a curved portion of said path. 120

7. A mechanical movement, having, in 130

- combination, a member mounted for movement in a curved path, and mechanism for moving said member along said path comprising a plurality of devices, each operative to move said member in a path different from that in which it is moved by the other devices and each being constructed and arranged to transfer said member to another of said devices.
10. 8. A mechanical movement, having, in combination, a member mounted for movement in a curved path, and mechanism for moving said member longitudinally of said path comprising two reciprocating devices and a rotatable device, all of said devices being arranged to engage said member and move it along said path and said rotatable device being operative to transfer said member from one of said reciprocating devices to the other.
9. A mechanical movement, having, in combination, a member mounted for movement in a path having straight and curved portions, means for moving said member along a straight portion of said path and additional means for moving it along a curved portion of said path.
10. A mechanical movement, having, in combination, a plate having a curved slot therein, a member movable longitudinally of said slot, and mechanism for moving said member along said slot comprising a plurality of devices each movable in a fixed path and each operative through engagement with said member to move it along a portion of its path into engagement with another of said devices.
11. A mechanical movement, having, in combination, a plate provided with a slot having a straight portion and a curved portion, a member movable in said slot, and mechanism for moving said member back and forth longitudinally of said slot comprising a reciprocating device operative to move said member through the straight part of said slot and a rotatable device operative to move said member through the curved portion of said slot.
12. A mechanical movement, having, in combination, a moveable member, and mechanism constructed and arranged to act directly on said member to give it a bodily oscillating movement in a substantially U-shaped path, said mechanism comprising two reciprocating devices arranged to move said member through the straight portion of said path, a rotatable device for moving said member through the curved portion of said path, and guiding means for holding said member in engagement with said devices.

In testimony whereof I have signed my name to this specification.

CHARLES C. BLAKE.
